CLAIM

The ornamental design for a lanyard connector, as shown and described.

DESCRIPTION

FIG. 1 is a perspective view of a lanyard connector showing my new design;

FIG. 2 is a front view of the lanyard connector shown in FIG. 1;

FIG. 3 is a back view of the lanyard connector shown in FIG. 1;

FIG. 4 is a first side view of the lanyard connector shown in FIG. 1;

FIG. 5 is a second side view of the lanyard connector shown in FIG. 1;

FIG. 6 is a perspective view of a second embodiment of a lanyard connector showing my new design;

FIG. 7 is a front view of the lanyard connector shown in FIG. 6;

FIG. 8 is a back view of the lanyard connector shown in FIG. 6;

FIG. 9 is a first side view of the lanyard connector shown in FIG. 6; and,

FIG. 10 is a second side view of the lanyard connector shown in FIG. 6.
